UNITED STATES PATENT OFFICE.

ALTON F. JOHNSON, OF CHICAGO, ILLINOIS.

COAT-HANGER.

1,316,618.

Specification of Letters Patent. Patented Sept. 23, 1919.

Application filed July 8, 1918. Serial No. 108,131.

To all whom it may concern:

Be it known that I, ALTON F. JOHNSON, a citizen of the United States, residing at Chicago, in the county of Cook and State 5 of Illinois, have invented new and useful Improvements in Coat-Hangers, of which the following is a specification.

This invention relates to coat hangers, and particularly to a safety clamp applica- 10 ble thereto.

An object of my invention is to provide a safety clamp of the character described, which will have a soft and yielding action upon the dress or coat hung upon the coat 15 hanger, so that while securing the article, at the same time it will not tear or ruffle the same.

Another object of my invention is to provide a coat hanger of the kind described 20 which will safely hold a garment, but which will permit the same to be dislodged by a violent jerk or pull, thus preventing the tearing of the garment.

Another object of the invention is to pro- 25 vide a safety garment hanger, which will positively lock a garment in position with any desired degree of force, thus making it possible to lock overcoats or the like with sufficient force to firmly secure the same 30 without locking fine garments with force enough to tear or ruffle them.

Other objects and advantages of the in- 35 vention will appear as the description to follow proceeds.

35 In the drawings,

Figure 1 is an elevation of a coat hanger with my clamp applied thereto.

Figs. 2, 3, and 4 are similar views of 40 modifications of the invention.

40 Reference now being had to the drawings, numeral 1 represents a coat hanger of ordinary construction, provided with a shank 2, having a hook 3. Rigidly mounted upon the hanger portion 1 are a pair of clamps 4, bolted thereto as indicated, to which are pivoted the blades 5, overlying the arms of the hanger. Springs 6 serve to keep the blades 5 clamped upon the hanger 1, springs 45 6 and blades 5 being upturned at their inner ends to provide finger hold 7, whereby the blades may be lifted at the same time the shank 2 is grasped to support the hanger in the hand and to permit the removal or attachment of a garment thereto.

55 In Fig. 2 is a modification of the form

shown in Fig. 1, showing springs 6' of a slightly different form.

In Fig. 3 is another modification, in which the blades 5 are pivoted by cross pins 9, passing through forked extensions 10 therefrom and through the hanger 1, a spring 11 being attached to the lower ends of the extensions 10 to provide resilient pressure.

60 Fig. 4 is a modification substantially the same as that shown in Fig. 3, in which view 65 the blades 5 are provided with raised portions 12 to accommodate a coat collar or the like.

The degree of pressure with which the garment is locked is controlled by the force 70 with which the ring 18 is pushed down. Thus, light silken waists and the like may be locked with a very light pressure, while heavy overcoats and the like may be locked with pressure sufficient to hold them in 75 place. In all of the modifications, the curve of the blades 5 is so designed, and the blades are so arranged that they will come down evenly all over the hanger 1 so as to avoid rubbing and possibly tearing delicate fab- 80 rics.

Having now described my invention, I claim—

1. A garment hanger comprising a curved support, locking blades pivotally mounted 85 on said support, resilient means normally causing said blades to press for a substantial portion of their length against the upper face of said support, a shank projecting upwardly from said support, and upwardly extending finger grips on said blades so positioned on each side of said shank that as the shank is held in one hand the finger grips may be engaged by the fingers of said hand for movement toward said 90 shank to operate said locking blades.

2. In a garment hanger, a support, cross pins fixedly mounted with relation to said support, locking blades normally engaging the upper face of said support for a sub- 100 stantial portion of their length and pivotally mounted on said pins whereby to eliminate any sliding movement of said blades longitudinally of said support as they are swung toward or away therefrom, 105 and resilient means associated with said blades to cause them to normally press against said support.

3. In a garment hanger, a support, lock- 110 ing means pivotally mounted upon said sup-

port, resilient means for causing said locking means to engage said support to lock a garment thereon, and finger pieces associated with said locking means to release 5 the same, said locking means being located above the support and so formed as to provide a space for the collars of coats and the like.

4. In a garment hanger, the combination 10 of a support for a coat or the like, a member for sustaining said support, a pair of arms for clamping a garment to said support, pivotally mounted on said support and normally engaging the upper face thereof 15 throughout a substantial part of their length, on either side of said sustaining member whereby to have movement in the arc of a circle only and resilient means for causing said clamping means to perform 20 their clamping function.

5. In a garment hanger, a support, a pair 20 of locking blades for clamping a garment to said support, said blades being pivotally

mounted on said support and normally engaging the upper face of the support, resilient means for causing said blades to normally press against said upper face, said blades each having an upwardly extending projection at its inner end to serve as finger grips. 25

6. In a garment hanger, a support, locking blades pivotally mounted on the upper side of said support, the clamping portions of said blades being parallel with said upper side whereby to eliminate any longitudinal sliding movement of said clamping portion when being pressed against said support, and resilient means for causing said blades to normally press against said support. 30

In witness whereof, I hereunto subscribe 40 my name to this specification in the presence of two witnesses.

ALTON F. JOHNSON.
